UNITED STATES PATENT OFFICE.

CHARLES L. SPINNEY, OF LYNN, MASSACHUSETTS, ASSIGNOR TO GENERAL ELECTRIC COMPANY, A CORPORATION OF NEW YORK.

INDUCTION-MOTOR.

1,091,713.

Specification of Letters Patent. Patented Mar. 31, 1914.

Application filed September 30, 1912. Serial No. 723,047.

To all whom it may concern:

Be it known that I, CHARLES L. SPINNEY, a citizen of the United States, residing at Lynn, county of Essex, State of Massachusetts, have invented certain new and useful Improvements in Induction-Motors, of which the following is a specification.

The present invention relates to the construction of induction motor armatures, and 10 particularly to the casting of windings upon the iron core.

The well-known squirrel-cage induction motor armature, or rotor, consists of a cylindrical iron core in which are embedded 15 conductor bars ordinarily consisting of copper. These conductors are connected at each end by what is known as short-circuiting rings, or simply end rings. The bars formerly have been mechanically inserted in 20 the core and either soldered, or welded to the end rings or the end rings have been cast against the drawn conductors. These operations are necessarily expensive. Soldering has an additional disadvantage, for 25 when the motor is operated at an overload the resulting high temperature is apt to cause the soldering metal to melt, and injure the motor. The invention of Dr. Ezechiel Weintraub for a method of casting 30 copper as disclosed in Patent #1,023,604 of April 16, 1912, has made it possible to cast both the copper conductors and end rings in position in a single operation. Although 35 small sized rotors may be cast without special difficulty and without change of the design heretofore used, it has been found that difficulty is experienced when casting the winding of large rotors. The end rings shrink in size, causing a radial stress upon 40 the conductors toward the shaft, and resulting in rupture either of the bars or end rings. I have discovered that this difficulty may be avoided by inclining or canting the projecting ends of the conductor bars to 45 the ends of the core at an angle less than 90 degrees, preferably about 45 degrees. When bars of a rectangular section are used it is advisable sometimes but not necessary to arrange the mold so as to give a twist or 50 turn to the projecting ends of the bars, rotating the major axis outside of the core at an angle to the major axis within the core, in this manner bringing the strains caused by shrinkage of the end ring to bear upon 55 the lesser diameter.

My invention will be pointed out with greater particularity in the appended claims.

For a more complete understanding of my invention reference may be had to the accompanying drawings taken in connection 60 with the following description.

Figure 1 is a front elevation partly in section of a completed rotor; Fig. 2 is a fragmental sectional side view showing how the ends of the bars are twisted; Fig. 3 is 65 an enlarged fragmental perspective view of a single bar and Fig. 4 is a somewhat diagrammatic view showing the relations of the twisted ends of the bars.

Referring to Fig. 1 the core 1, commonly 70 consists of laminations of magnetic steel, or iron clamped together by plates 2, 2'. Through this core pass conductor bars 3, shown particularly in the sectional part of the core just below shaft 4. As here illustrated 75 the bars extend longitudinally through the core at right angles to the core sides but this is not necessarily the case. The ends of the bars project some distance beyond the core substantially within an extension of a cylindrical surface of the core and are integrally bound together by end rings 5, 5'. The projecting ends of the bars, or pins, 6 between the core and the short-circuiting rings are inclined about 60° 80 or less with respect to the core face, substantially in a plane parallel to the axis of the core, as clearly shown in Fig. 2. In other words, instead of projecting at right angles to the core face, they are bent at an angle of at least 30° usually about 45° out of a vertical position, as best shown in Fig. 85 3. It is not necessary that the inclinations be in opposite directions as here shown. The reasons why this method of casting 90 the rotor prevents cracking of the bars, I believe to be twofold. In the first place the pull of the shrinking end rings is more in the nature of a twist than a bend. In the second place, I believe it is due to the fact that parts which are already bent require less stress to be bent still further. The twisting or partial rotation of the pins 6, as illustrated particularly in Fig. 4 and by sections 7 and 8 in Fig. 2, is used in some 95 cases when the bars have a substantially rectangular cross-section. In this manner the radial inward stress caused by the shrinking of the ring is more easily taken 100 up by the projecting pins. 105 110

The above construction, of course, will apply also to metals other than copper, such as brass which may be used in case higher resistance armatures are desired.

5. What I claim as new and desire to secure by Letters Patent of the United States, is,

1. An induction motor rotor comprising a magnetic core, conductors passing therethrough and projecting outside said core at 10 an angle of less than 90 degrees with respect to the face of said core, the projecting ends of said conductors being located substantially within an extension of the cylindrical surface of the core and a short-circuiting ring connecting and forming an integral part of said conductors.

2. In an induction motor, the combination of an iron core, cast metal bars passing therethrough and projecting beyond said 20 core, said projecting ends extending at an angle of about 45 degrees to a line passing longitudinally through said core and located substantially within an extension of the cylindrical surface of the core, and a cast conductor short-circuiting said bars.

3. An induction motor rotor, comprising a cylindrical core of magnetic material, copper conductors passing longitudinally through said core near its peripheral surface 30 and extending beyond the ends of said core, said projections being eanted at an angle of

less than 60 degrees, and copper rings binding the respective ends of said conductors together, said conductors and rings forming a single mass of copper without mechanical joints. 35

4. An induction motor rotor comprising a cylindrical iron core, substantially rectangular bars passing through said core so that the major axes are radially disposed, the 40 ends of said bars projecting beyond the sides of the core at an angle less than 90 degrees said projecting ends being rotated or twisted so as to incline the major axes and a metal ring integrally connecting said bars. 45

5. An induction motor rotor, comprising a cylindrical iron core, substantially rectangular cast copper bars passing through said core near its peripheral surface and having their major axes radially disposed, the ends 50 of said bars projecting beyond the faces of said core at an angle less than 90 degrees, said projecting ends being located substantially in a plane parallel to the axis of said core and a cast copper ring integrally connecting said bars. 55

In witness whereof, I have hereunto set my hand this 27th day of September, 1912.

CHARLES L. SPINNEY.
